Patented Dec. 22, 1925.

1,566,305

UNITED STATES PATENT OFFICE.

ROLAND C. BROWN, OF MILWAUKEE, WISCONSIN.

METHOD OF MAKING BLUE PRINTS WITH DARK LINES AND WHITE FIELDS.

No Drawing.

Application filed November 6, 1923. Serial No. 673,205.

To all whom it may concern:

Be it known that I, ROLAND C. BROWN, a citizen of the United States, and a resident of the city of Milwaukee, county of Milwaukee, and State of Wisconsin, have invented certain new and useful Improvements in Methods of Making Blue Prints with Dark Lines and White Fields; and I do declare the following to be a clear, exact, and complete description of the same, such as will enable persons skilled in the art to which the invention pertains to practice the same.

The invention relates to the art of producing blue-prints of drawings or other sheets having upon the face thereof the delineations and characters which it is desired to reproduce, in multiple copies it may be.

Ordinarily, a tracing of the drawing is made, and this, in the form of a positive, is imposed upon the surface of a sheet of blue-printing paper and subjected to the action of light rays, with the result that the print appears as a negative or reverse, with the delineations and characters in white and the field in dark blue. Such prints are not highly desirable, but are acceptable in many instances by reason of the great economy with which the results can be obtained.

Another method involves the intermediate step of making a negative from the tracing in the form of a brown or Van Dyke print, which when imposed upon a sheet of blue-printing paper and subjected to the action of light, will result in a blue-print having dark blue delineations and characters upon a white field. Prints of this nature are much superior to those produced by the practice of the method first described and are highly desired by reason of their clearness, but the performance of the intermediate step of making the Van Dyke negative adds greatly to the cost of production.

My improved process enables me to produce blue-prints of the more desirable class, that is, with dark lines and white fields, in a much more expeditious and economical manner.

The practice of my invention involves the use of a sheet of impression or transfer paper, one surface of which is completely coated with a composition of opaque matter, applied but lightly thereto, and adapted to be removed therefrom by the application of pressure exerted upon the other side of the sheet. By means of such pressure, the mat-

ter of the composition at the points or lines in which the pressure is applied is removed from the impression or transfer sheet, with the result that the opaque transfer sheet is converted into a negative having clear lines and points at the places where pressure was applied and with an unbroken coating over the other portions of its surface.

The negative thus produced is directly imposed upon a sheet of blue-printing paper and exposed to the action of light, the rays of which pass through the open lines and points and react upon the surface of the blue-printing paper exposed through the negative. The undisturbed opaque coating covering the other portions of the surface of the impression or transfer sheet prevents the light from acting upon other than the indicated portions of the blue-printing paper. As a result, a blue-print is produced on which the dark delineations and characters thereof are emphasized by the surrounding white field.

Having thus outlined the general nature of my invention, I will now proceed with a description of a specific application of the improved process, and will point out the novel features of the invention in the appended claims.

It being desired to produce blue-print copies of a drawing, I impose an impression or transfer sheet such as described upon a plain sheet of paper, which I term a "checking sheet." Upon the impression or transfer sheet the drawing is superposed, and the delineations and characters of the latter are traced by a stylus or other suitable implement. The pressure exerted in the operation of tracing the drawing acts to remove the coating from the opaque impression or transfer sheet in the lines and points of such pressure and transfer such coating to the checking sheet, so as to convert the impression or transfer sheet into a negative in which the lines and characters of the drawing are sharply delineated by contrast with unbroken opaque coating covering the remainder of the negative.

At the conclusion of the tracing operation, the checking sheet will be found to reflect faithfully all of the delineations and characters of the drawing which have been traced. Comparison of the checking sheet with the drawing will enable the accuracy of the negative to be determined, so that cor-

rection of the latter in any necessary particular, as by subtraction or addition, may be made.

Erasures may be made upon the coated 5 surface of the negative, and the erased portions again coated by the use of a carbon pencil or suitable composition for further tracing. Surplus marks and characters may be eliminated by coating in the same manner.

After the negative thus produced has been ascertained to be correct, its coated surface may be fixed and preserved from damage by spraying thereover a light protecting 15 coating of a suitable hardening liquid, such as white shellac. After being treated in this manner, the negative may be handled without liability to disturbance of its surface or the delineations and marks thereon.

20 The negative created in the manner described is placed with the blue-printing paper in a printing frame or machine, as usual in making blue-prints, the sensitized blue-printing paper being affected by the 25 rays of light which pass through the open places in the negative, so that a positive blue-print having the most desirable appearance which it is possible to attain in such matters is produced expeditiously and 30 economically. The elimination by my process of the older practices of making an ink tracing of the drawing and the intermediate Van Dyke negative, are material economical 35 advantages which flow from the present invention.

The drawing may be produced co-incidentally in the tracing operation after first 40 superposing a blank sheet of drawing paper upon the coated sheet, or the drawing to be traced may have been previously executed. In either case, it is the pressure exerted in the formation of the delineations and char-

acters in one instance, or in following them in the other, that effects the transfer of the coating from the prepared sheet so as to 45 break the surface of the latter and produce the negative.

Having thus described my invention, what I claim and desire to secure by Letters Patent of the United States, is:

1. The process of making a blue-print with dark delineations and characters upon a white field, which consists in imposing upon a plain sheet, an impression or transfer sheet provided upon its underside with an opaque coating and superposing a drawing thereon, tracing the drawing to produce upon the plain sheet a replica of such drawing for checking purposes and convert the impression sheet into a negative by the transfer of the coating to the plain sheet in the tracing operation, fixing the coating upon the negative by applying a preservative thereto, and printing copies upon sensitized paper by passing light rays through the 60 open lines of the drawing.

2. The process of making a blue-print with dark delineations and characters upon a white field, which consists in arranging a drawing upon a coated opaque impression 70 or transfer sheet, tracing the drawing by pressure to remove the coating of the sheet in correspondence with the traced delineations and characters and convert the coated sheet into a negative of the drawing, fixing 75 the coating upon the negative by applying a preservative thereto, and printing copies upon sensitized paper by passing light rays through the open lines of such negative.

In testimony whereof, I have signed my 80 name at Milwaukee, this 30th day of October, 1923.

ROLAND C. BROWN.
